United States Patent Office.

OTTO SLIKER, OF LINCOLN, ILLINOIS.

Letters Patent No. 91,978, dated June 29, 1869.

IMPROVEMENT IN DOOR-HOLDER.

The Schedule referred to in these Letters Patent and making part of the same.

To all whom it may concern:

Be it known that I, OTTO SLIKER, of Lincoln, in the county of Logan, and State of Illinois, have invented a new and useful Improvement in Door-Holders; and I do hereby declare the following to be a full and correct description of the same, sufficient to enable others skilled in the art to which my invention appertains to fully understand and use the same, reference being had to the accompanying drawings, which make part of this specification, and in which—

Figure 1 is a perspective view of one form of my invention;

Figure 2 is a perspective view of the same when attached for use;

Figure 3 is a longitudinal section of the same; and

Figure 4 is a detached view of part of the same.

Like figures of reference indicate like parts in the several figures.

The nature of my invention consists in providing a door-holding knob, which is to be fastened to the washboards with an expanding V-spring, which, when the door is opened to its full extent, catches in a socket in the door, and is again released when the door is to be closed, by the power exerted in doing so.

A, fig. 1 of the drawing, represents a shank, extending at one end into a screw, *a*, and at the other into two bent arms or expanding springs *B* *B'*, which end in half-spherical projections *C*.

On the spring *B'*, near its projection *C*, is formed a ring or band, *D*, in which a cushion, *G*, of any elastic or yielding material is secured, projecting beyond the ring *D*.

E is a plate, provided with a hole, *e*, in its centre, of a diameter less than the distance between the projections *C* from each other, and attached to the lower part of the door, over a hole, or cavity, formed in the latter, of sufficient size to admit the projections *C* of the springs.

In fig. 3 a modification of my device is shown.

F is a knob provided at its smaller end with a screw, *a*, and having a recess, *b*, formed in its opposite end for the reception of a circular cushion, *c*, of yielding or elastic material.

The ends of the springs *B* are provided with projections *C*, as described, and are held in place by a pin, *d*.

The operation of my device is very simple, and easily understood.

The springs, fig. 1, being attached to the washboard and the plate *E*, over the cavity in the door, as shown in fig. 2, when the latter is thrown open to its full extent, for the purpose of retaining it, the hole *e* flies over the projections *C*, the same being rounded or semispherical, compressing them in that act, and the plate *E* striking against the cushion *G*, thus preventing a great noise and jar.

As soon as the projections *C* have passed through hole *e*, they are allowed to again expand, and thus hold the door securely.

The device shown in fig. 3 acts in the same way, the cushion *c* preventing the noise and jar. The door is released by the mere force exerted in closing it.

Having thus described my invention,

What I claim as new, and desire to secure by Letters Patent, is—

1. The expanding springs *B* *B'*, when provided with convex or semispherical projections *C*, in combination with plate *E*, provided with hole *e*, as shown, and for the purpose described.

2. In combination with the above, the ring or band *D* and cushion *G*, as shown, and for the purpose described.

OTTO SLIKER.
